CIRCUIT CONTROL DEVICE

Stanford R. Ovshinsky, Detroit, Mich., assignor to Tann Corporation, Detroit, Mich., a corporation of Michigan

Filed Apr. 7, 1958, Ser. No. 726,663

8 Claims. (Cl. 200—112)

This invention relates to control devices, and particularly to a device which controls the passage of an electric current.

The present invention pertains to a device having an internal compartment containing a dielectric fluid, the chamber being separated into compartments by a porous diaphragm. At least one of the divided compartments contains a plurality of conducting or nonconducting particles which are compacted to form a conducting or insulating path between conductors connected to a circuit. While compacting the particles along a path in one of the divided compartments, the other half of the compartment may have the particles dispersed along a path between contacts connected in a second circuit and passed through the diaphragm into the first said compartment. Instead of permitting the particles to pass therethrough, the diaphragm may trap the particles and become conductive to complete a circuit across conductors which are joined thereto. Thus, a difference in potential applied across the dielectric fluid controls the compacting of the particles to a desired degree, depending upon the voltage which is employed across the compartment. The greater the voltage the greater the compacting of the particles, and therefore the more current which may be carried when the particles are conducting.

A conducting liquid may be employed for passing from one to the other side of the diaphragm for completing a circuit in one section of the compartment while interrupting a circuit in the other section thereof. The control of the path by the difference in potential thereacross may be augmented by a magnetic flux control separately or in combination with the potential control to require the presence of multiple signal means for passing and/or interrupting the current.

Accordingly, the main objects of the invention are: to provide a device which is controlled by a difference in potential to produce a change in state in a path through the device to control the conductivity of the path; to make the properties of a fluid in a device conducting by moving the particles therein through a diaphragm; to form a compacted conducting path by a difference in potential applied across the device; to apply a potential across the diaphragm within a device which compacts conducting particles therein to control the conductivity of a current path; to form a conducting path across the contacts of a device to which a circuit is joined to pass current therethrough upon the application of a potential across the device, and, in general, to provide a control device for a circuit which is simple in construction, positive in operation and economical of manufacture.

Other objects and features of novelty of the invention will be specifically pointed out or will become apparent when referring, for a better understanding of the invention, to the following description taken in conjunction with the accompanying drawing, wherein:

Figure 1 is a sectional view of a device for controlling an electric circuit embodying features of the present invention;

2

Fig. 2 is a view of structure, similar to that illustrated in Fig. 1, showing a further form of the invention;

Fig. 3 is a view of structure, similar to that illustrated in Fig. 1, showing another form which the invention may assume, and

Fig. 4 is a view of structure, similar to that illustrated in Fig. 2, showing still another form of the invention.

The device of the present invention controls the passage of current by a change in state of a material which 10 bridges spaced conductors within the length of the device. For example, the device illustrated in Fig. 1 has an insulating body 10 containing an internal chamber 11 divided into two sections by a porous diaphragm 12 which may be metal, parchment membrane, or other 15 material which has minute openings therethrough. A dielectric liquid 13, which may be of the silicon type having different viscosities, is placed within the chamber and a plurality of conducting particles 14 of silver, copper or the like are suspended in the liquid. An electrode 20 15 is mounted at one end of the device opposite to an electrode 16 mounted in the other end thereof. A circuit 17 is connected to the electrodes through a signal device 18, the circuit providing a difference in potential across the electrodes from a voltage source 19. A circuit is 25 connected to a pair of contacts 21 in one of the sections of the chamber and a second circuit is connected to a pair of contacts 22 located across the other section of the chamber. As illustrated in the figure, the area on the lower section of the chamber below the diaphragm 30 has its status changed from a nonconductive to a conductive one by the attraction of the particles downwardly through the diaphragm 12 into the lower section where they are compacted into a conductive path. When the path bridges the contacts 22, current will flow in the 35 connected circuit, and as more and more particles are moved into the lower section, a greater and greater amount of current can be passed across the contacts. As the particles pass from the upper section of the chamber into the lower, less and less current will be carried; 40 across the contacts 21 and the circuit joined thereto is quickly broken. In this manner, a circuit through one of the sections of the chamber may be broken while a circuit through the other section is completed to a greater or lesser extent, depending upon the amount of compacting 45 which occurs to the particles. When the signal device is again operated, a difference in potential occurs across the electrodes 15 and 16, causing the particles to move upwardly through the diaphragm 12 until all of the particles have moved into the section of the chamber 50 above the diaphragm, thereby interrupting the circuit through the contacts 22 while completing a circuit across the contacts 21.

In Fig. 2, a similar device is illustrated, that wherein, coils 23 and 24 are placed in opposite ends of the housing 55 10 to produce magnetic fields on the particles 25 within the dielectric liquid 13 when the particles are made of a magnetizable material. In the figure, the coils are placed about the electrodes 15 and 16 which may be employed separately as described above when a difference in potential is applied thereacross, or in combination with a magnetic field, or the magnetic field may be employed separately without applying the potential across the electrodes. When the coils are used alone or with the electrodes, the play of signals in the circuits thereto will control the circuits across the contacts 21 and 22. The particles will travel from the upper to the lower section or from the lower to the upper section when the axis of the housing is in a vertical plane or from one to the other end when the axis is in a horizontal plane, depending upon which coil is energized. The movement 60 of the particles may be prevented by applying a bias potential to a circuit 32 across the diaphragm 12. The 65 70 75 80 85 90 95

potential applied across the diaphragm blocks the passage of the particles therethrough when the flux from one or the other or both coils attempts to move the particles past the diaphragm from one to the adjacent section of the chamber. From this it will be understood that a further control is provided for completing the circuits 21 or 22 by a signal which completed a circuit to the coil 23 which will prevent the particles 25 from moving into the adjoining section if a potential is present across the diaphragm. It is necessary to have a second signal oppose and therefore remove the potential from across the diaphragm before the particles may pass to complete the contacts 21 or 22.

In Fig. 3, a further form of the device is illustrated, that wherein an insulating body 26 has a hollow chamber 27 divided into two sections by a diaphragm 28 of one of the types above referred to. A circuit 29 is completed in the left-hand section by the conducting liquid 30, while a circuit 31 is interrupted in the right-hand section. As herein illustrated, the conducting liquid 30 fills the left-hand section of the chamber, thereby completing the circuit 29 while the right-hand chamber is empty, causing the circuit 31 to be interrupted. When a potential is applied across the diaphragm in one direction by the circuit 32, the liquid 30 in one section will pass through the diaphragm into the other section. By applying the potential to the diaphragm in opposite directions, the fluid will move from one side of the diaphragm into the other, completely emptying the one and filling the other side of the hollow interior.

In Fig. 4, a device similar to that of Fig. 3 is illustrated, having, in addition, electrodes 35 and 36 mounted at opposite ends so that when no potential is present across the diaphragm 28 of porous metal sheet or screen from the circuit 32, a difference in potential applied across the electrodes 35 and 36 will force the particles to pass through the diaphragm from one to the other end of the device in the liquid 13 within the hollow interior thereof. By reversing the flow of the potential, the particles can be forced to move either to the right or left section of the chamber, which movement, as the case may be, may be blocked by a potential in the circuit 32 across the diaphragm 28. When a potential is applied to the circuit 32, the particles will collect on the diaphragm and will complete a circuit 39 connected to the contacts 37 and 38 supported on the diaphragm. Insulating sleeves 40 are disposed about the contacts 37 and 38 and secured to the diaphragm, thereby insulating the contacts therefrom. With this arrangement, the conducting particles may be compacted in either section of the compartment or on the diaphragm and may make or break circuits connected to the contacts 21 or 22 or across contacts 37 and 38.

When the word "particle" is employed throughout the specification and claims, it is to be understood that true spherical particles are not necessarily referred to since the particles may be of any shape and may vary in size, depending upon the size of apertures in the diaphragm. Such particles can be magnetic, conductive, or nonconductive, since they will be affected by the applied difference in potential across the electrodes and be moved in a manner to change the conductivity of a path, as hereinabove described. This change of state of the variable medium of the device will change the degree of conductivity of a path to interrupt or complete a circuit, as the case may be.

What is claimed is:

1. In a control device for a circuit, a housing having an internal chamber, a diaphragm dividing said chamber into two sections, contacts extending into at least one of said sections to which a circuit may be secured, a liquid within said housing, means at opposite ends of the housing providing an electrostatic field when connected to a supply circuit, said diaphragm being porous, and conducting particles within said liquid which pass through said diaphragm into a section which becomes conductive.

2. In a control device for a circuit, a housing having an internal chamber, a diaphragm dividing said chamber into two sections, contacts extending into at least one of said sections to which a circuit may be secured, a liquid within said housing, means at opposite ends of the housing providing an electrostatic field when connected to a supply circuit, said diaphragm being porous, and conducting particles within said liquid which pass through said diaphragm into a section which becomes conductive when a difference of potential is applied across said electrodes to produce said field.

3. In a control device for a circuit, a housing having an internal chamber, a diaphragm dividing said chamber into two sections, contacts extending into at least one of said sections to which a circuit may be secured, a liquid within said housing, means at opposite ends of the housing providing a field when connected to a supply circuit, said diaphragm being porous, conducting particles within said liquid which pass through said diaphragm into a section which becomes conductive, and a coil located at each end of said housing which produces a magnetic field when energized to move said particles when of magnetizable material with or in opposition to that produced by said electrostatic field.

4. In a control device for a circuit, a housing having an internal chamber, a diaphragm dividing said chamber into two sections, contacts extending into at least one of said sections to which a circuit may be secured, a liquid within said housing, means at opposite ends of the housing providing a field when connected to a supply circuit, said diaphragm being porous, conducting particles within said liquid which pass through said diaphragm into a section which becomes conductive, and a coil located at each end of said housing which produces a magnetic field when energized to move said particles when of magnetizable material, said electrostatic field being also applicable to said particles by a difference in potential across said electrodes separately and in combination with the magnetic field produced by said coils.

5. In a control device for a circuit, a housing having an internal chamber, a diaphragm dividing said chamber into two sections, contacts extending into at least one of said sections to which a circuit may be secured, a liquid within said housing, means at opposite ends of the housing providing a field when connected to a supply circuit for rendering said liquid conductive in said one section for completing a circuit across said contacts, and means for applying a difference in potential across said diaphragm for preventing the passage of the particles therethrough.

6. In a control device for a circuit, a housing having an internal chamber, a diaphragm dividing said chamber into two sections, contacts extending into at least one of said sections to which a circuit may be secured, a liquid within said housing, means at opposite ends of the housing providing a field when connected to a supply circuit for rendering said liquid conductive in said one section for completing a circuit across said contacts, means for applying a difference in potential across said diaphragm for preventing the passage of the particles therethrough, said particles rendering said diaphragm conductive, and spaced contacts on said diaphragm between which a conducting path is completed.

7. In a control device for a circuit, a housing having an internal chamber, a diaphragm dividing said chamber into two sections, contacts extending into at least one of said sections to which a circuit may be secured, a liquid within said housing, means at opposite ends of the housing providing a field when connected to a supply circuit for rendering said liquid conductive in said one section for completing a circuit across said contacts, contacts on said diaphragm connectable in a circuit, and means for applying a potential across said diaphragm for collecting and compacting particles thereon which bridge the contacts on the diaphragm and complete a circuit thereacross.

8. In a control device for a circuit, a housing having an

internal chamber, a diaphragm dividing said chamber into two sections, contacts at opposite ends of said diaphragm, a liquid within said housing, means at opposite ends of the housing providing an electrostatic field when connected to a supply circuit, said liquid having dielectric properties, and conducting particles in said liquid which render said diaphragm conducting when collected thereon to complete a circuit between said contacts.
